MEANS FOR MAKING STITCHED OPENWORK

Antonio Turrisi, New York, N. Y., assignor to
 Maiden Form Brassiere Company, Inc., New
 York, N. Y., a corporation of New York

Original application March 10, 1938, Serial No.
 195,065. Divided and this application July 25,
 1940, Serial No. 347,400

16 Claims. (Cl. 112—217)

This application is one of two divisions of my application for United States Letters Patent, Serial No. 195,065, filed March 10, 1938, which parent application, after having been co-pending for a time with said divisional applications, did mature into United States Letters Patent 2,219,460 on October 29, 1940.

This invention relates broadly to new means for making stitched open work.

One of the objects of this invention is the provision of simple, practical, rugged and economical means adapted to ready embodiment in existing standard sewing machine constructions, after the embodiment of which such sewing machine constructions may be utilized to receive fabric portions provided with a line of loose stitches and deliver them connected by ornamental stitched open work.

Another object of this invention is the creation of suitable apparatus and means for so treating and stitching fabric portions already connected by a line of loose or slack stitches, that when the treatment and stitching is finally completed, the fabric portions are connected by a practical, rugged, useful and ornamental stitched open work.

A still further object of this invention is the provision of such novel apparatus and parts as I have found are beneficial and/or desirable to produce the resulting desired ornamental stitched open work.

These and many other objects are secured by the invention hereinafter disclosed. Various further and other objects and advantages of the invention other than those hereinabove specifically mentioned, will appear more fully herein-after.

It is to be understood that the specific forms shown in the accompanying drawing are merely illustrative, and hence the description thereof is not to be taken as limiting.

This invention resides substantially in the parts, as well as in the combination, construction, arrangement and relative location of parts, all as will appear more fully herein-after.

Referring to the drawing, wherein like reference numerals are used throughout the several views to indicate the same or similar parts, it will be found that:

Figure 1 represents a side elevational view taken on line 1—1 of Figure 2 with some parts broken away, of my novel means in association with a double needle machine for treating and stitching work after the same has been provided with an appropriate line of slack stitching; this

view also showing part of the work in advance of and part of the work to the rear of the presser foot of this machine;

Figure 2 represents a sectional view taken along the section line 2—2 in Figure 1, looking in the direction of the arrows;

Figure 3 represents a top plan view of the construction for securing to and holding on the presser-foot bar, the separating finger device shown in Figure 1; the presser-foot bar in this view being shown in section;

Figure 4 represents a top plan view of the separating wheel I employ in the structure shown in Figures 1 and 2, and the plate member and its extension on and by which the same is rotatably carried, part of which plate is broken away;

Figure 5 represents a broken away view showing in section a portion of the work after the same has been stitched by the double needle stitch machine of Figures 1 and 2.

As is well known, numerous efforts have heretofore been made from time to time to provide a relatively simple, cheap, rugged and easily embodiable apparatus for use in sewing machines for joining fabric sections together by a line of practical, rugged, useful and ornamental stitched open work. Thus, in the art of sewing, it is often highly desirable to join two fabric portions together with ornamental stitched open work instead of by a mere plain line of closed seam. A cogent example of where fabric sections might preferably be thus joined, is to be found in the art of fabricating brassière pockets by the joining together of at least a single pair of fabric edges

35 by durable stitching which is also highly ornamental. Thus, the form-fitting breast-receiving pocket of a brassière is often produced by the securing together of two irregular shaped fabric members, to wit: an upper pocket section and a lower pocket section, along a bent line of seam. In the production of such a garment, it is obviously invaluable from all angles including that of effecting a satisfactory joinder, that of ornamentation and that of ventilation, to produce the

40 pocket by the provision of an ornamental line of stitched open work which is effective to join the upper and lower sections, rather than a mere bent line of closed seam. It will be understood that there are innumerable different types of garments, 45 articles of wearing apparel and other articles wherein stitched open work has been long found to be equally desirable. Numerous efforts have been made to provide ready apparatus for producing such ornamental and useful stitched open work. In the provisions of a suitable apparatus

50

for producing this desired effect it is, of course, desirable that the apparatus to be employed be readily adaptable to use in conjunction with and readily embodiable in existing standard sewing machines without any material or substantial alteration or modification of the construction or parts thereof.

Such efforts as have been directed to the solution of this problem, as far as I have found, have not met with widespread commercial adoption and success, for the reason I believe, that they necessitate extensive changes in the construction of existing standard machines or else a high degree of specialized skill on the part of the operator in the operation of a specified attachment of one sort or another. Accordingly, it is my purpose to herein disclose an economical, simplified and cheap means for producing the desired stitched open work, which neither involves radical departure from existing standard sewing machine constructions or parts, nor a high degree of specialized skill in the manipulation and operation of a peculiar specific type of attachment.

My aforementioned Patent 2,219,460 the application for which was co-pending herewith, describes a mechanism adjusted for ready embodiment in existing standard sewing machine structure which stitches together two fabric portions and in Figure 4 of the drawing of that patent the fabric portions are shown as an upper portion 29 and a lower portion 30 joined together with a line of slack stitches so as to leave a selvage to each of said portions and to which selvages further reference will be made shortly. My present invention contemplates that these selvages be each folded back against its respective fabric body portion and that the fabric pieces with their respective folded back selvages be separated and drawn apart at and upon the successive slack stitches and that in this procedure the portion of the lower fabric piece 30, lying to the left of the free end portion 24 of element 20 (reference is here had to Figure 4 of Patent 2,219,460) be drawn away from the corresponding adjacent portion of the upper fabric piece 29, and down towards the bottom of the needle thread loops until the portion of fabric piece 30 rested against the bobbin thread 32 at the bottom of such loops. Since the successive loops of needle thread 31 are of uniform size, such a drawing of fabric portion 30 away from fabric portion 29 leaves such fabric portions uniformly spaced apart by a distance equal to substantially one-half of the length of thread in a given loop, but joined at each and every successive original pierce point of the needle 3 by two substantially equal lengths of needle thread, to wit, the needle side limb 31a of each needle thread loop and the work side limb 31b of such needle thread loop, the length of such limbs being substantially each one-half of the entire length of the thread comprising the final needle thread loop which leaves the free end of portion 24 of element 20.

As will be observed from an inspection of Fig. 5, when the portions 29 and 30 of the work are drawn apart and the respective selvages are folded back against their respective bodies, the selvage 30a will have resting against the line of fold thereof with the fabric portion 30 the bobbin thread 32, which it will, upon being folded back, encompass, while the selvage 29a will have resting against the line of fold thereof with the fabric portion 29 the successive lengths of needle thread which run from and join one original pierce point of needle 3 with the next adjacent

and succeeding original pierce point of needle 3, which successive lengths of needle thread the portion 29a will encompass upon being folded back. Accordingly, it will be understood that, by providing, in the double needle sewing machine shown in Figs. 1 and 2, suitable apparatus for separating the selvages and folding each selvage back against its joined fabric body portion and separating and drawing apart the fabric body portions with their folded back selvages, the selvages 29a and 30a thereupon may be simultaneously each stitched to their respective fabric bodies 29 and 30. When the selvage 29a has been folded back against the fabric portion 29, thereby encompassing the successive lengths of the needle thread which join one original pierce point of needle 3 with the next adjacent and succeeding original pierce point of needle 3, and the selvage 30a has been folded back against the fabric portion 30, thereby encompassing the bobbin thread 32; and the fabric portion 29, with folded back selvage 29a, and the fabric portion 30, with folded back selvage 30a, have been separated and drawn apart to the maximum extent possible and the selvages 29a and 30a have been stitched respectively in the thus drawn apart position, the desired ornamental open work is formed.

Thus, observing the portion of the fabric pieces lying, in Fig. 2, to the left of the heel of presser foot 38, it will be observed that the fabric portions 29 and 30 are there shown with the edges formed by the folding over of their respective selvages 29a and 30a uniformly and evenly separated and spaced apart over the length thereof, but joined and connected by a continuous series of successive spaced apart substantially equal thread lengths transversing the open space lying between the edges formed by the folding over of the selvages aforesaid. At this point, it should be understood that each original pierce point of needle 3, in the fabric portion 29, will be joined to the corresponding original pierce point of needle 3 in the fabric portion 30 by the two substantially equal lengths of thread, to wit, the limbs 31a and 31b of the series of loops of needle thread 31.

Upon viewing Figures 1 and 2 of the drawing of my present application, it will be observed that I there show a presser foot 38, having openings 39 and 40, in which a pair of needles 41 and 42 may work. Presser foot 38 is carried by a conventional presser-foot rod or bar 43 and such presser foot 38 is provided, as shown, with a single solid central curved toe 44, having a longitudinally extending elongated opening 45 therein, which opening preferably extends through said toe from top to bottom thereof. Rotatably mounted on or slightly above the bed plate of this machine is a freely rotatable toothed wheel 46 having teeth 47. Wheel 46 is adapted for rotation about an axis substantially perpendicular to the direction of travel of the work and, upon rotation of wheel 46, a portion of the teeth 47 thereof will pass through the opening 45.

Secured on element 43, I provide a collar 48, which may be moved along element 43 and vertically adjusted and set at a desired position therealong by any suitable holding device, such as by means of set screws 49 as shown in Figures 1 and 3, or the like. It should be understood that this collar and the elements carried thereby are accordingly susceptible of adjustment in relative vertical position with respect to the bed plate of this machine and the work resting thereon. This collar 48, as may be observed in Figure 3, is pro-

vided with an extended portion 48a, which in turn is provided with a hole extending transversely therethrough, adjacent the end wall 48b of the collar 48. Through said hole a rod-like element 54 extends. This element 54 is of a length substantially greater than the transverse width of portion 48a of collar 48. Accordingly, element 54 may be moved through the hole in portion 48a and extended out from portion 48a to a suitable extent by the operator of the machine. When finally placed in desired position, the element 54 may be firmly held in adjusted position by any suitable means, such as by the wing nut set screw 55, or the like. Secured at the outermost end of element 54 is an extension 50, which preferably is integral with element 54 and of slightly larger cross-sectional area than element 54, or the hole in portion 48a through which the element 54 extends, whereby a shoulder 50a is provided at the union between 54 and element 50. It will be understood that since the extension 50 and the shoulder 50a are of slightly greater diameter than the diameter of the transverse hole extending through portion 48a, such shoulder, by abutment with the external surface of portion 48a, will act to limit the amount to which elements 54 and 50 may be pushed back to the rear, through the hole in portion 48a. Element 50 is bent as at 51 into a rod-like element portion 51a, which has a center axis substantially perpendicular to that of element 50. Element portion 51a extends in said direction, that is, along the said line perpendicular to the axis of element 50 and parallel to the bed plate of the machine, until the general plane defined by the axis of the presser-foot bar 43 and the longitudinal center line of the presser foot 38 is reached, at which place element 51a is also bent and a further element portion or vertical arm portion 52 thereupon extends downwardly substantially in the last mentioned general plane and parallel to the axis of presser-foot bar 43; that is, element portion 52 has a center axis which is substantially perpendicular to that of element portion 51a. This vertical downwardly extending arm portion 52 has a lower portion thereof formed with beveled sides, that is, such element portion 52 has its lower portion formed into a tip, which tapers downwardly providing the end portion 53, which is adapted to act as a fabric separating finger.

It will be understood, of course, that the element just described, to wit: that composed of the portions 54, 50, 51a, 52 and 53, is preferably a single element appropriately machined, bent, configured and shaped, that is, with each of the mentioned portions thereof being formed integrally with the next adjacent portion.

It will be further understood that such portions, however, need not necessarily be integrally joined, but rather the parts or portions may be so constructed and arranged in any fashion that will suitably produce appropriate adjustable support for the separating finger 53. Thus, each of the portions could be made separately and joined to its next adjacent portion by any suitable securing device, such as by a collar, with a set screw or the like; or the separating finger 53 might be supported by any other means which would permit of suitable adjustable positioning of the said separating finger 53; all within the scope of my invention. Accordingly, it will be understood that I do not desire that my invention be deemed in any way limited to the specific adjustable separating finger supporting construction, which I

have hereinbefore described as being preferable, but rather desire that the same be considered as illustrative.

As will be observed from an inspection of Figures 1 and 2, to the right in each case of the presser foot 38, the fabric work piece portions 29 and 30, which have been provided with the line of slack stitch, are placed in the positions there shown therefor, with the one fabric portion 29 lying to one side of the presser foot 38, and the other fabric portion 30 lying to the other side of the presser foot 38; and with the selvages 29a and 30a standing upwardly. That is, the fabric portions 29 and 30 are separated, spread out and laid upon the bed plate of the double-needle sewing machine with the said portions extending away from each other and being positioned so that the line of slack stitch, the selvages 29a and 30a and a small portion of the fabric of the bodies of each of the portions 29 and 30, adjacent the line of lock stitch and the selvages, will pass under the presser foot 38. When the work has been thus disposed, the presser foot 38 is lowered into position so that the needles 41 and 42 may thereafter work in the holes 39 and 40 to provide lines of stitches in the fabric passing therebeneath by feeding action of the usual feeding mechanism. The position of the separating finger 53 is then adjusted so that the same lies between the two selvages 29a and 30a, a suitable distance in advance of the tip of the toe 44 of presser foot 38, and a slight distance above the line of slack stitch joining the fabric portions 29 and 30, all so that the finger 53 will act as a separating element in advance of the presser foot 38, without contacting or interfering therewith or with the thread loops of the line of slack stitch. The separating finger 53 may be thus set by extending element 54 out from portion 48a of collar 48 and fixing the same in suitable horizontal position by tightening the wing set screw 55; and, further, by setting the collar 48 at suitable vertical position on the presser-foot bar 43 and fixing such collar at such vertical position by tightening of set screws 49.

It will be understood that the separating finger 53, standing out thus in advance of the tip of the toe 44 of presser foot 38, will act to separate the selvages 29a and 30a as they are subsequently fed towards and under the presser foot 38 and, accordingly, the separating effect of such finger will be automatically continuous.

Turning now again to Figs. 1 and 2, it will be observed that on the right in each of said figures, the work is shown with the fabric portion 30 and its selvage 30a not yet drawn apart from the fabric portion 29 and its selvage 29a. As the work is fed towards and under the presser-foot 38, the upstanding selvages 29a and 30a are separated by the separating finger 53 interposed therebetween. As the work continues on from the separating finger 53 towards the presser-foot 38, the teeth 47 of wheel 46 enter into the spaces between the successive loops of the needle thread 31 and uniformly separate and draw apart the fabric portions 29 and 30 to the maximum extent possible; that is, until the portions 29 and 30 are separated by a distance substantially equal to one-half of the length of the thread of each loop of the needle thread 31. For this purpose, it will be understood that the width of the teeth 47 is such that suitable separation and drawing apart is effected thereby; and, further, that the number of teeth on the circumference of the rotatable wheel 46 is such that such successive teeth will

enter into successive spaces between the needle thread loops. Thus, the limbs **31a** and **31b** of one loop will enter into and lie between two teeth **47** while the limbs of the next similar loop, will enter into and lie in the next space between teeth **47**, and thus the teeth will fix the successive thread limbs **31a** and **31b** of one loop in appropriate position relative to those of the next loop, and the fabric portions **29** and **30** will be simultaneously appropriately spaced apart. It will be also understood that, as the selvages **29a** and **30a** go towards and under the presser-foot **38** and as the teeth **47** enter into successive spaces between successive needle thread loops, the selvages **29a** and **30a** are, as they pass under the toe of the presser-foot **38**, folded back against the respective fabric portions **29** and **30**. As the work thereupon progresses further under the presser-foot, the needles **41** and **42**, operating in the holes **39** and **40**, provide suitable lines of stitches **56** and **57**, whereby the selvages **29a** and **30a** are sewn back to the respective bodies of fabric portions **29** and **30**, and the thus treated work is thereupon fed out from under the heel of the presser-foot **38**, provided with the desired ornamental stitched open work. A plan appearance of the stitched-back selvages against the respective fabric portions will be observed in Fig. 2, to the rear of the presser-foot **38** and a cross-sectional view of such fabric, provided with my stitched ornamental open work, will be observed in Fig. 5.

In further connection with my double needle stitch machine, it will be noted that in Figs. 1 and 4, I show the manner in which the toothed wheel **46** is rotatably supported. Thus, it will be observed that I have shown said wheel rotatably carried by a tongue **46a** which extends out from a plate **46b**, which plate is adapted to be mounted on or slid into the general plane of the bed plate of said machine. I have shown the tongue **46a** with a bifurcated end **46c**, having the tines of such end joined adjacent the tips thereof by a pin **46d**, which runs transversely of such tines and the space lying therebetween, on which pin the said wheel **46** is freely rotatably mounted.

I deem the structure which I have just described, for supporting the rotatable wheel **46**, as being preferable for attaining the purpose desired therefor. However, since it is conceivable that other suitable supporting means for maintaining the wheel **46** in proper operating position might be found advantageous and suitable for such purpose, I desire, of course, that my description of such construction shall be interpreted as illustrative and not as in any sense limiting.

It, accordingly, will be understood from all of the foregoing that by the employment of my invention, which I have herein disclosed, fabric pieces may be joined by a highly ornamental stitched open work of desirable character.

From the foregoing, it will be obvious that while I have described my invention in connection with certain machine constructions, my invention might with equal advantage be employed with other constructions. Thus, my finger, the utilization of which results in slack stitching, might be embodied in different types of sewing machines; and the stitching back of fabric selvages may possibly be found to be advantageously carried out by a plurality of operations on a single needle machine. Likewise, it is conceivable that other modifications and/or variations might be found desirable and/or advantageous.

Inasmuch, therefore, as many changes may be made in the above constructions, and many ap-

parently widely and different embodiments within the scope of the invention may be made without departing from the spirit and scope thereof, and inasmuch as my invention may reasonably be used for many purposes, it is intended that all matters hereinabove contained or shown in the accompanying drawing shall be interpreted as illustrative and not as in any sense limiting.

What I seek to secure by and claim for United States Letters Patent is:

1. In a mechanism of the type described for stitching-back selvages to the respective bodies of fabric portions joined by slack stitching, a selvage separating finger, means for holding each of the separated selvages against the body of the fabric portion of which it is part; a rotatable stitch-separating toothed wheel disposed between said means and said finger, means for stitching each such selvage to said body, and means for advancing the fabric portions successively to the aforementioned separating finger, toothed wheel, holding means and stitching means.

2. In a mechanism of the type described for use on a sewing machine having a needle and a bed plate, a plate adapted for securement to the sewing machine bed plate, an elongated tongue-like extension carried thereby, said elongated extenison having a bifurcated end, a pin running transversely of the tines of said bifurcated end and carried thereby and a freely rotatable stitch-separating toothed wheel rotatably mounted on said pin between said tines, with the teeth of said wheel projecting through the plane of the bed plate in advance of the needle.

3. In a sewing machine having a work support, a presser foot, and a pair of laterally spaced reciprocable needles for forming parallel lines of stitches in adjacent fabric portions, said presser foot comprising a main body portion having apertures for passage of said needles therethrough, and an upturned toe portion having an elongated opening therein, and a fabric-separating toothed wheel supported by said work support for free rotation below said opening with the teeth thereof movable in said opening upon rotation thereof.

4. The structure recited in claim 3, characterized in that the mentioned presser-foot has the toe thereof curved to aid in separating and folding back fabric selvages against fabric bodies prior to stitching of such selvages back to said bodies.

5. In a sewing machine for making ornamental stitched open work from two pieces of stitched fabric which are joined by a line of slack stitching, the combination of means for uniformly separating the fabric pieces to the extent permitted by the line of slack stitching, said means including a freely rotatable toothed wheel, the successive teeth of which are adapted to successive insertion between successive slack stitches, means for simultaneously folding over the selvage of each piece of fabric against the body of the fabric thereof and means for simultaneously stitching each selvage to its body in separated position and means for advancing the work for successive treatment by each of the aforementioned means in the order mentioned.

6. The structure recited in claim 5 characterized in that the means for folding over the selvage of each piece of fabric against the body of the fabric thereof includes a presser-foot which is so shaped as to progressively fold over the sel-

vage as the work is advanced towards the stitch position.

7. In a sewing machine for making ornamental stitched open work from two pieces of fabric which are united by slack stitching, the combination of means for advancing the work, a freely rotatable toothed wheel, the axis of rotation of which wheel extends transversely to the general direction of work advance and lies substantially in the same general plane in which works the aforesaid advancing means and the teeth of which wheel are adapted, upon advancement of the work, to successively enter, between the two pieces of fabric, into the successive spaces lying between the loose stitches to separate the fabric pieces and means for fixedly holding such fabric pieces in separated position.

8. In a sewing machine for making ornamental stitched open work from two pieces of fabric which are united by slack stitching, the combination of means upon which the body of each of the fabric pieces may be arranged so that both bodies lie in substantially the same general plane and with the selvages upstanding, means, including a freely rotatable toothed wheel, for uniformly separating the fabric pieces to the extent permitted by the slack stitching, means for folding back the selvage of each fabric portion against the body thereof, means for stitching each selvage back to its body portion and means for advancing the work, over the first mentioned means, successively to and through the position of said wheel, said folding means and said stitching means, in the order named.

9. In a sewing machine of the type described, a plate over which two pieces of fabric united by slack stitches may be advanced for a further stitch-forming operation and a toothed stitch-separating wheel so mounted with respect to said plate that it may freely rotate in the direction of work advance with its axis of rotation substantially in the plane of work advance and with the teeth thereof successively projecting through the spaces lying between the successive slack stitches in the work.

10. The structure recited in claim 9 characterized in that the stitch separating toothed wheel is so proportioned that the space between successive teeth thereon will accommodate two threads and the teeth thereon be adapted for insertion between successive slack stitches.

11. In a serving machine of the type described for stitching back selvages to the respective bodies of fabric work portions, which portions are already joined by slack stitching, the combination of means upon which the bodies of such work portions may be arranged so that said bodies lie in substantially the same general plane while the selvages thereof upstand therefrom, means for advancing the work to and through a stitching position, means for separating the selvages and fabric bodies to the extent permitted by the slack stitching upon advance of the work, a toothed stitch-separating wheel so mounted with respect to the first mentioned means that, upon advance of the work, it may freely rotate in the direction of work advance with the teeth thereof successively projecting through the spaces lying between the successive stitches which join the work portions to uniformly equalize the separation of fabric between stitches, means for folding, and for holding each of the separated selvages back in folded condition against the body of the fabric work portion of which it is a

part, and means, at the aforementioned stitching position, for simultaneously stitching each such selvage to its corresponding body portion.

12. In a sewing machine of the type described for stitching back selvages to the respective bodies of fabric work portions, which portions are already joined by slack stitching, the combination of means upon which the bodies of such work portions may be arranged so that said bodies lie in substantially the same general plane while the selvages thereof upstand therefrom, means for advancing the work to and through a stitching position, a toothed stitch-separating wheel so mounted with respect to the first mentioned means that, upon advance of the work, it may freely rotate in the direction of work advance with the teeth thereof successively projecting through the spaces lying between the successive stitches which join the work portions to uniformly equalize the separation of fabric between stitches, means for folding, and for holding each of the selvages back in folded condition against the body of the fabric work portion of which it is a part, and means for stitching each selvage to its corresponding body portion.

13. Fabric selvage separating mechanism for use with a sewing machine including a presser bar having a presser foot carried thereby and a pair of needles reciprocable through openings in the presser foot, said separating mechanism comprising a rod-like element adjustably supported by and extending therefrom perpendicular to the presser bar and parallel to the longitudinal center line of the presser foot to one side thereof, the rod-like member being laterally deflected and terminating in a vertically disposed separating finger having its free active end in advance of the presser foot and in the longitudinal center thereof, and means for securing said rod-like member in adjusted position for varying the distance between said free active end and the presser foot.

14. The structure recited in claim 7 characterized in that the means for fixedly holding the fabric pieces in separated position includes a presser foot having a single solid central curved toe to fold and hold the selvage of each fabric piece back against the body thereof and means for stitching each selvage to its corresponding body portion in such position.

15. Fabric selvage separating mechanism for use with a sewing machine including a presser bar having a presser foot carried thereby and a pair of needles reciprocable through openings in the presser foot, said separating mechanism comprising means engageable with said presser bar for vertical adjustment thereon, a rod-like member adjustably supported by and extending from said means perpendicular to the presser bar and parallel to the longitudinal center line of the presser foot to one side thereof, the rod-like member being laterally deflected and terminating in a vertically disposed separating finger having its free active end in advance of the presser foot and in the longitudinal center thereof, and means for securing said rod-like member in adjusted position for varying the distance between said free active end and the presser foot.

16. The structure recited in claim 15 characterized in that means are provided for limiting the closeness of approach of said separating finger to said presser-foot bar.
